CLAIM

(21) Appl. No.: **29/124,047**

The ornamental design for a frame for packing pieces for a fireproof lead-through in walls and other construction elements, as shown and described,

(22) Filed: **May 30, 2000**

DESCRIPTION

(30) **Foreign Application Priority Data**

Nov. 29, 1999 (SE) 99-2134

FIG. 1 is a front perspective view of a frame for packing pieces for a fireproof lead-through in walls and other construction elements, showing my new design;

(51) **LOC (7) Cl.** **25-02**

FIG. 2 is a rear perspective view thereof;

(52) **U.S. Cl.** **D25/60**

FIG. 3 is a front elevational view thereof, and,

(58) **Field of Search** 174/48; D25/60,

FIG. 4 is a side elevational view thereof, seen from the left of FIG. 1, the opposite side thereof being identical thereto.
